CLAIM

The ornamental design for a bear front footprint tread for a legged robot, as shown and described.

DESCRIPTION

FIG. 1 is a top view of the invented design for a bear front footprint tread for a legged robot.

FIG. 2 is a top perspective view thereof.

FIG. 3 is a rear view thereof.

FIG. 4 is a front view thereof.

FIG. 5 is a left side view thereof.

FIG. 6 is a right side view thereof; and,

FIG. 7 is a bottom view thereof.

Broken lines depict portions of the bear front footprint tread for legged robot and form no part of the claimed design.

1 Claim, 7 Drawing Sheets
